HIGH-FREQUENCY TUBE STRUCTURE

Donald L. Snow, Hempstead, N. Y., Edward L. Ginzton, Redwood, Calif., and Donald R. Hamilton, Princeton, N. J., assignors to The Sperry Corporation, a corporation of Delaware

Application March 14, 1947, Serial No. 734,690

12 Claims. (Cl. 315—5)

1

This invention relates, generally, to ultra-high-frequency electron beam velocity-modulating devices and, more specifically, to improvements in the type of single-resonator ultra-high-frequency reflex tube disclosed in Fig. 2 of U. S. Patent No. 2,250,511 for "Oscillator Stabilization System," issued July 29, 1941 in the names of Russell H. Varian and William W. Hansen. The present application is a continuation in part of application Serial No. 447,536 filed June 18, 1942 and which issued October 21, 1947 as U. S. Patent No. 2,429,243.

At very high frequencies, the component parts of such electron beam tubes become very small. For example, the resonator must be of such a size that resonator walls of suitable thickness are comparable in dimension to the depth of the resonator. Other problems, such as closeness of entrance and exit grid spacings, make simplicity of design necessary. When such devices are used as local oscillators, as in aircraft receivers, low electron-beam-accelerating voltages are used, resulting in low power output. Thus, elimination of either the entrance or exit grid becomes desirable as these grids stop electrons of the beam and thus cause a further reduction in power.

The conventional reflex electron beam velocity-modulating tube contains a cathode, an entrance grid, an exit grid, and a reflector plate. The present invention provides novel means for eliminating either the entrance or the exit grid.

It is therefore an object of the present invention to provide a novel electron beam velocity-modulating ultra-high-frequency oscillator, also adaptable for use with or as a mixer, in which the exit grid is eliminated.

Another object lies in the provision of such a device in which the reflector electrode is placed in the position formerly occupied by the exit grid.

A further object is to provide filter means to prevent the escape of ultra-high-frequency energy past the reflector plate, which must necessarily be insulated from the resonator body itself.

Another object lies in the provision of velocity modulating devices, compactly designed and with a minimum number of grids, so that active electrons are not removed from the beam and fewer secondary electrons are formed.

A still further object is to provide arrangements whereby the electrons traverse different paths on entering and leaving the resonator.

Still another object is to provide means outside the resonator for absorbing spent electrons of the electron beam.

Other objects and advantages will become ap-

parent from the specification, taken in connection with the accompanying drawings wherein the invention is embodied in concrete form.

In the drawings,

Fig. 1 is an elevation cross-section view of a form of tube claimed in Patent 2,429,243 which eliminates the resonator exit grid.

Fig. 2 is an explanatory graph.

Fig. 3 is a fragmentary cross-section view of a modified portion of Fig. 1 showing means for concentrating the electron beam.

Fig. 4 is a fragmentary cross-section view of a modified portion of Fig. 1 showing electron absorption means.

Fig. 5 is a cross-section view of an alternate form of a portion of Fig. 1 showing novel coupling means.

Fig. 6 is an elevation cross-section view of an alternate form of Fig. 1.

Fig. 7 is a fragmentary cross-section view of a modified portion of Fig. 6.

Fig. 8 is an elevation cross-section view of a form of the invention which eliminates the resonator entrance grid.

Fig. 9 shows a form of the invention which is a partial cross-section view of a modified form of Fig. 1 that has means exterior to the resonator for absorbing spent electrons.

Fig. 10 is a further modified form of Fig. 1.

Similar characters of reference are used in all of the above figures to indicate corresponding parts.

Referring now to Fig. 1, there is seen an elevation cross-section view of an embodiment of the present invention especially useful at very short wavelengths. A cathode emitter surface 1 is supported in a focusing cylinder 4 on which is mounted a mesh wire grid 3 directly in front of emitter 1, both cylinder 4 and the hot cathode being supported from insulator 5. Lead wires 2 feed current to a heater coil (not shown) inside of cathode 1. Voltages are applied to leads 2 and to focusing shield 4 by means of leads 6, 7 respectively, which pass through the glass portion 8 of the vacuum envelope. The cathode structure is centrally positioned in a cylindrically apertured conducting member 9, which also supports resonator entrance grid 10 parallel to cathode emitter surface 1. Grid 10 may consist of alternate short and long conducting radial grid wires. Member 9, together with flexible conducting diaphragm 12 mounted thereon, forms one wall of a cavity resonator, the remainder of the resonator being enclosed by resonator body 11.

As shown in Fig. 2 of the aforementioned U. S.

Patent No. 2,250,511, there is usually provided opposite the entrance grid 10 and positioned centrally in resonator body 11, a second or exit grid similar to grid 10, through which the electrons from cathode 1 pass. After the electron beam leaves the resonator it is reflected back thereto by means of a reflector electrode operating at or near the potential of the cathode. If an ultra-high-frequency electromagnetic field exists within the resonator, the electron beam undergoes recurrent velocity changes by the action of the field during the beam's initial passage through the resonator. As the electron beam passes beyond the resonator toward the reflector electrode, the effect of the velocity modulation is to commence recurrent grouping of the electron beam. The spacing between the resonator exit grid and the reflector electrode, and the voltage on said electrode are so arranged that the electrons are reflected back into the resonator at a time when the velocity modulation has resulted in density modulation producing electron groups and the electron groups return energy to the electromagnetic field thereby maintaining it. Direct current, introduced into the device by means of the electron beam, is thus converted into ultra-high-frequency energy and may be removed from the resonator by means of coupling loops and associated concentric line elements.

In the present embodiment of the invention, however, the exit grid is dispensed with, and the reflector plate is introduced in a novel and useful manner. As seen in Fig. 1, the reflector surface 18 is positioned substantially flush with the inner conducting surface of resonator body 11. The surface 18 is the flat end surface of a quarter-wave long cylinder 19, which forms a portion of the first section of a low-pass filter consisting of an outer cylindrical conducting tube 17 surrounding concentrically an inner conducting member comprising approximately quarter-wave long sections 19, 20, 21, 22 which are alternately large and small in diameter. The last small diameter section 22 of the filter protrudes through glass-to-metal seal 23, thus providing support for the inner conductor of the filter. The filter is provided in order that a voltage equal to the cathode voltage, or some other desirable voltage may be supplied to reflector surface 18 without the loss of ultra-high-frequency energy from the oscillating electromagnetic field inside the resonator. Any number of filter sections may be employed; however, four alternately large and small diameter sections ordinarily provide adequate attenuation. The design and operation of such filters have been described in copending application Serial No. 417,229, entitled "High Frequency Tube Structure," filed October 31, 1941 in the name of William W. Hansen, now Patent No. 2,506,590.

Energy may be removed from the resonator by coupling loop 24, which is shown at the termination of coaxial line 25. In very short wave devices of this type, the resonators may be so small that coaxial lines of conventional size cannot conveniently be utilized; consequently line 25 is made very small in diameter. Both conductors are expanded in tapered section 26 to adapt the line to a section 27 of normal size. Continuity of the vacuum envelope is provided in line 27 by the glass-to-metal seal 28. Tubular outer conductor 29, with its threaded flanged portion 14, serves in the conventional manner as a connector to a conventional coaxial line to

lead energy to utilization apparatus. Additional coupling loops may be supplied, if desired.

A spider, fixed on reentrant member 9 and having three legs 13 spaced opposite three legs 15 attached to resonator body 11, forms, together with screws 16, means for tuning the resonator by variation of the space between grid 10 and reflector 18, in the well known manner. Other well known tuning devices, as shown in later figures, may be used if desired.

One mode of operation of the device may be described with reference to Fig. 2, illustrating an idealized graph of space potential as a function of distance between the cathode 1 and the reflecting surface 18. The reflector is assumed to be at cathode potential, and the effects of space charge are neglected. As seen in Fig. 2, the potential on any electron in the space between cathode 1 and reflector surface 18 is an increasing function of the distance from cathode 1. After passing through grid 10, the electron is acted upon by a field which is the sum of a constantly decreasing potential and the alternating potential due to the ultra-high-frequency oscillating field between grid 10 and reflector 18. Dotted lines 48, 48' represent extreme conditions of this resultant field. Electrons, accelerated by the direct voltage between emitter 1 and grid 10, pass through grid 10 with a uniform velocity, and while traversing the space from grid 10 to their point of reflection and back through the grid 10, are velocity modulated in the conventional manner. After passing through grid 10 in the reverse direction, the electrons are reflected in front of the cathode structure and are again directed through grid 10. During this last reflection, the electron beam has become density-modulated, and returns to the space between grid 10 and reflector 18 to give up energy to the oscillating electric field therebetween, thus maintaining electromagnetic oscillations in the resonator. It is seen that the distance between grid 10 and the point of reversal of the paths of the electrons in front of reflector 18 and cathode 1 is determined by the flight time necessary to bring the density modulated beam into the oscillating electric field at the proper instant to give up energy to that field.

Analysis of another mode of operation of the device shown in Fig. 1 may also be made similar to the analysis of operation of the electron beam velocity modulating reflex devices disclosed in the above mentioned U. S. Patent No. 2,250,511. Electrons from emitter 1 are focused into a slightly converging circular cross section beam by focusing shield 4, and have been accelerated by the cathode voltage on reaching entrance grid 10. In traveling from grid 10 toward reflector surface 18, the beam is velocity modulated. With proper interelectrode spacings, and with the proper reflector voltage, all of the electrons are reflected before reaching surface 18 and travel again toward grid 10. During the interval of reflection, the velocity modulation of the electron beam has resulted in density modulation, in such a manner that these electrons give up energy to the oscillating field thus maintaining it. It is again seen that interelectrode distances are determined by the necessary electron transit time.

If the voltage impressed on reflector surface 18 is not sufficient to reflect those electrons which are most accelerated during the velocity modulation process, they will be collected by the

reflector. Surface 18 may be provided under such circumstances with a secondary electron suppressing material. The action may be spoken of as electron beam density modulation by absorption. Suppose that all electrons passing grid 10 during the half of the cycle in which the oscillating field aids the beam acceleration voltage strike the reflector 18 and are collected. These electrons remove energy from the field. Electrons entering the resonator one-half cycle later find the oscillating field opposing their motion, and thus supply energy to the field. These electrons are so decelerated by the retarding potential of reflector 18 that they are reversed in direction without striking the reflector. As the reflected electrons travel back toward grid 10, the oscillating field has again reversed; consequently the electrons again add energy to the field. The result is a positive addition of energy to the oscillating electromagnetic field, so that the field is maintained. The device of Fig. 1, as well as alternate forms to be further discussed in connection with later figures may thus operate as simple velocity modulation device, or as an absorption density modulation device, as desired.

Fig. 3 illustrates a slight modification in the configuration of the electrodes of the device of Fig. 1. The cathode and heat or focusing shield 4 are seen to be similar to those of Fig. 1. The radial grids 10 of Fig. 1 are, however, replaced by a knitted or woven grid 30, which is preferably made of a conducting material or may be plated with a conducting material. The grid 30 is made to bow away from the focusing shield 4 into the resonator space. The first section 19' of the filter is modified so that its upper reflecting surface 18' is concave. The surface 18' may be parallel to the surface 30 or may not, as desired. The actual configuration is empirically adjusted to give best focusing of the electron beam, and it seems evident that one skilled in the art may use many modifications of the grid and reflector plate shapes shown in Figs. 1 and 3.

If the device of Fig. 1 is operated by the absorption bunching principle, the modification shown in Fig. 4 is useful. In this figure the first section 19'' of the filter is modified so that the reflecting surface 18 of Fig. 1 is replaced by a grid 33 which may be a woven or knitted grid. The cylinder 19'' is made hollow and contains in its bottom a reentrant conical projection 34. In operation, the electrons which pass the grid 10 at a time when the oscillating field in the resonator accelerates them, pass through the grid 33 and are collected by the Faraday cage action of the element 19''. The cone 34 is provided so that secondary electrons emitted when high energy electrons strike its surface will not be reflected back into the resonator cavity. Alternatively, if desired, the surface 18 of the reflector may be coated with a secondary emission substance, so that density modulation is caused when high speed velocity modulated electrons strike the surface 18. It will be clear that the reflecting electrode of any of the modifications to be described may be similarly coated.

With reference to Fig. 1 it was stated that for very small wavelength devices of this type it may sometimes be difficult to introduce coupling loop 24 and its associated coaxial line. Fig. 5 shows a modification of the structure of Fig. 1 combining the energy-removing device and the filter through which the reflector voltage is introduced. Only section 19 of the filter is used, concentrically supported in an outer conducting tube 35 by an inner

conducting rod 46. Rod 46 is in turn supported by a rod 36 which passes out through a glass-to-metal seal 38 in the end of tube 35. At the junction between rods 36 and 46, rod 36 has a small diameter projection 47 which is a quarter wave long and which is inserted into a central hole in rod 46, rods 36 and 46 being insulated from each other by means of an insulating bushing 48 approximately a quarter wave long. Attached at right angles to rod 46 is a small-diameter inner conductor 40 which passes through a hole in outer tube 35. Outside of tube 35, conductor 40 is concentrically surrounding by a conducting tube 39. Near the outer end of tube 39 the inner conductor 40 is expanded into a section 43 almost equal the inner diameter of the tube 39 and insulated therefrom by an insulating bushing 44. Section 43 of the line is made approximately a quarter wave long and is terminated by a lead 45. A glass-to-metal seal 42 is provided to give continuity to the vacuum envelope.

In the operation of Fig. 5, a voltage equal to or near cathode voltage is applied to the lead 45 and is thus directly introduced to the reflector plate surface 18. The filter section 19 allows an arbitrarily chosen amount of energy to flow down the concentric line 46, 35 and may be designed so that a maximum amount of ultra-high-frequency energy can be removed from the resonator without overloading it and causing oscillations to stop. The insulating section 48 prevents the reflector voltage from going out on the inner conductor 36 to utilization apparatus, and the filter section 43 prevents ultra-high-frequency from leaking out into space, the coaxial line 39, 40 being designed to have very high impedance at the frequency used. The tube 35 is provided with a threaded flanged portion 37, to which a conventional coaxial cable may be attached. Filter section 19 may be a hollow Faraday cage similar to section 19'' of Fig. 4, if desired.

Referring now to Fig. 6, there is illustrated a modification of the device of Fig. 1 in which thermal tuning of the resonator is readily accomplished. The cathode structure may be similar to that previously described. A hollow resonator 55 is formed by a centrally apertured conducting plate 56, a cylindrical conducting tube 57, and a conducting member 58 with a protruding portion 54. Portion 54 has a surface 53 that may be utilized as a reflecting electrode. Tube 57 is extended to provide the outer conductor of a coaxial filter whose inner conductor comprises alternately large and small portions 58, 59, 60, and 61. A centrally apertured conducting plate 63 closes the tube 57 and terminates the filter. The last small diameter portion 61 of the filter consists of a thin walled conducting tube which has an extension 65 projecting through the aperture in the plate 63. Extension 65 is concentrically surrounded by a tube 64 attached to the plate 63. A glass seal 66 between tubes 64 and 65 provides continuity to the vacuum envelope as well as an insulating support for the inner filter structure. This construction allows the surface 53 to be maintained at a desired potential with respect to the entrance grid 10 while preventing radiation loss from the resonator 55 through the glass seal 66. Tube extension 65 contains a cartridge or other type of heater 62 to which power is applied by leads 68 passing through an insulator 67. Power applied to the heater 62 causes expansion of the thin walled tube 61, 65; consequently the spacing between the entrance grid 10 and the reflecting surface 53 is altered by the motion transmitted down the entire inner conductor of the

filter. Thus the resonant frequency of the resonator 55 may be varied at will in the well known manner. It will be clear that similar tuning means may be applied to any of the modifications described in the present specification.

Electrical tuning may be readily effected in the device of Fig. 6 by variation of the voltage applied to the reflector electrode 53. As is well known in the art, such a tuning method is most useful with low Q, high shunt impedance resonators. If the protruding portion 54 and the electron beam are made very small in diameter as compared to the diameter of the resonator, a low Q resonator results. If desired, these features may be combined in the device of Fig. 6, electrical tuning being used to provide changes over small frequency ranges, and thermal tuning being employed to provide changes over large ranges. If desired, the protruding portion 54 of the resonator 55 may be omitted, as seen in Fig. 7. In this case resonator 55 has a very high Q and has a considerably lower effective shunt impedance than the resonator 55 of Fig. 6.

Referring now to Fig. 8 there is illustrated a form of the invention in which the entrance grid to the resonator is omitted, an exit grid being supplied. An emitter surface 81 of a cathode 80 is placed coincident with the usual position of the entrance grid and a filter is provided around the cathode 80. The cathode 80 has a long tubular heat shield mounted on insulating washer 82 and is supplied with heating power by leads 83 connecting to leads 86 which pass out of the vacuum envelope through glass-to-metal seals 87. Concentrically surrounding the cathode tube 80 are small and large diameter conducting cylindrical tube sections 89, 90, 91, 92 and 93 respectively. Annular plates 94, 95, 96 and 97 connect adjacent dissimilar diameter tube sections to provide electrical and structural continuity. The tube 80 together with the composite outer conductor form a low pass filter which functions similarly to the filter of Fig. 1. It is to be understood that the two forms of the filter may be interchangeably employed according to mechanical convenience. A lead 85, passing through the glass seal 87 and connecting to a lead 84, is provided to maintain the cathode at the desired negative potential. The last portion 93 of the filter is fastened to an annular plate 98 which comprises, together with cylindrical tube 103 and opposed apertured plate 101, the resonator 100. A cylindrical tube 110 supporting an exit grid 102 projects through the aperture in plate 101. A conventional reflecting electrode 108 mounted on a conductor 109 is held within the tube 110 in the proximity of the grid 102 by a glass seal 111 which both provides continuity to the vacuum envelope and electrical insulation for the conductor 109. Tuning of the resonator 100 is shown to be accomplished by a conducting or dielectric plug 113, which, by rotation of knob 115, may be inserted to a greater or lesser degree into the resonator. Reentrant glass tube 114 surrounding the plug 113 is sealed to a concentric metal tube 112 inserted in the side 103 of the resonator to provide continuity of the vacuum envelope. The operation of such a tuning device is to cause distortion of the electromagnetic field inside of the resonator, thus altering its natural frequency in a well known manner.

Fig. 9 shows a form of the present invention most useful when operated as a simple electron beam reflex velocity-modulating device. A cathode 130 is seen mounted in a concentric tubular

focusing shield 132 having at its outer end a focusing grid 131 which is substantially parallel to the emitting surface of cathode 130. An entrance grid 137 to a resonator 138 is made substantially conical, the cone pointing toward the center of the grid 131. The exit grid of the resonator is again omitted, the reflecting voltage being applied through a filter 143 to a conical protruding reflector 145 whose convex surface may be parallel to that of grid 137. Electrons from which energy has been extracted are now reflected toward a grounded annular plate 133 surrounding the focusing grid 131, so that substantially none of these electrons are allowed to strike the emitting surface of the cathode. Also, in this form of the invention, the incident electrons travel different paths from the reflected electrons, so that difficulties due to electron dispersion, and to the possibility of a further entry of the reflected electrons into the resonator are avoided.

Fig. 10 shows a slight modification of the device of Fig. 9 which is useful for a similar purpose. A cathode 170 is mounted with its axis of symmetry at an angle with the axis of symmetry of a resonator 174. The electron beam of cathode 170 is projected through a large opening in a wall 176 of the resonator 174 containing radial grid bars 177 and is again reflected by a reflector surface 179 supported by a filter 181 similar to that of Fig. 1. Spent electrons are allowed to pass through the grid 177 and are collected by conducting wall 175. It seems apparent that any desired method of tuning of the resonators of Figs. 9 and 10 may be used.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. High frequency apparatus comprising a cavity resonator having an entrance means through which an electron beam is adapted to pass, said resonator having exit means, a reflector electrode positioned adjacent said resonator exit means and insulated therefrom, said reflector electrode having a convex surface opposing the electron beam, means for projecting the electron beam into said resonator through said entrance means and toward the convex surface of said reflector, and means for applying a potential difference between said reflector and said resonator to cause said beam to be reflected by said convex surface along a path different from that of the projected electrons and outwardly thereof.

2. A generator of electromagnetic waves comprising an apertured electromagnetic resonator adapted to contain an oscillating field therein, non-planar electron-permeable means bowed outwards from the aperture of said resonator, means in said generator for producing an electron stream and for projecting the stream into said resonator through said permeable means to effect velocity modulation of the stream by the field within said resonator, means in said generator including an electrode extending into said resonator and insulated therefrom for opposing the electron stream to effect density modulation thereof between said electrode and said electron-permeable means, whereby said density-modulat-

ed stream delivers energy to the electric field to maintain the same, and means outside said resonator for absorbing the stream after delivery of energy to the field.

3. A high frequency tube structure comprising a hollow cavity resonator adapted to contain an oscillating electromagnetic field and having opposed apertured walls, a non-planar entrance grid formed in one of said walls and projecting outwardly from said resonator, and a reflecting electrode occupying an aperture in the opposed wall, said reflecting electrode having a centrally-projecting portion, whereby electrons reflected by said electrode pursue paths different from the incoming electrons.

4. A high frequency tube structure as in claim 3 further comprising electron receiving means located outside said resonator for collecting said reflected electrons.

5. A high frequency tube structure comprising a hollow cavity resonator adapted to contain an oscillating electromagnetic field and having opposed apertured walls, an entrance grid disposed in one of said walls and projecting outwardly from said resonator, and a reflecting electrode occupying an aperture in the opposed wall, said entrance grid and said reflector electrode having substantially parallel conical surfaces, whereby electrons reflected by said electrode pursue paths different from the incoming electrons.

6. High frequency apparatus comprising a cavity resonator having an entrance means through which an electron beam is adapted to pass, said entrance means comprising a conical grid structure, a reflector electrode forming a portion of the wall of said resonator and insulated therefrom, said electrode being conical and coaxially disposed with respect to said grid, means adjacent said grid for projecting an electron beam through said entrance grid toward said reflector electrode.

7. A high frequency tube structure comprising a hollow resonator adapted to contain an oscillating electromagnetic field and having opposed apertured walls, an outwardly extending conically-shaped entrance grid occupying an aperture in one of said walls, a conically-shaped reflecting electrode occupying an aperture in the opposed wall, means adjacent said grid for projecting a beam of electrons through said entrance grid for exciting electromagnetic oscillations within said resonator, and filter means including said reflecting electrode as an element thereof for preventing undesired radiation of the electromagnetic energy from said resonator by way of said electrode.

8. High frequency apparatus comprising a cavity resonator having an entrance means through which an electron beam is adapted to pass, a reflector electrode positioned adjacent an aperture in the wall of said resonator and insulated therefrom, means including a cathode for projecting an electron beam through said entrance means into said resonator toward said electrode, said electrode having a substantially conical portion facing said beam for reflecting

the latter backwardly and outwardly of its initial path through said resonator, thereby preventing said beam from again entering the cathode region.

9. A high frequency tube structure comprising a hollow resonator adapted to contain an oscillating electromagnetic field and having an apertured wall, cathode means on one side of said wall for projecting a stream of electrons through said wall and into said resonator, and means on the other side of said wall including a reflecting electrode having a convex surface for reflecting said electrons back toward said wall and along a path different from and extending outwardly of that of the projected electrons.

10. High frequency apparatus comprising comprising means including a cathode for projecting a stream of electrons along a first path, a hollow resonator along said first path adapted to contain an oscillating electromagnetic field and having an electron-permeable grid with a central convex portion located coaxially with said cathode and extending in the direction thereof, means including a reflecting electrode for reflecting said electrons back toward said grid and along a second path outwardly of said first path, said reflecting electrode being located coaxially with said stream projecting means and further having a central convex portion extending in the direction of said cathode.

11. A velocity modulation electron discharge device comprising a cathode electrode means for producing an electron beam, means coupled to said beam including a cavity resonator for velocity modulating said beam, and a reflector electrode means having a convex surface for reversing the direction of said beam to cause said beam to retrace said resonator along a path extending outwardly of the initial path, one of said electrode means providing part of the field boundary of said resonator.

12. Apparatus as in claim 11, further including filter means coupled to one of said electrode means for minimizing the leakage of high frequency energy from said resonator.
